C. M. WATROUS

BASE FOR TOY TELEPHONES

Filed June 8, 1922

FIG. 1.

FIG. 3.

FIG. 2.

FIG. 4.

Clifford M. Watrous,

BY

Clifford M. Watrous
ATTORNEY

UNITED STATES PATENT OFFICE.

CLIFFORD M. WATROUS, OF EAST HAMPTON, CONNECTICUT, ASSIGNOR TO GONG BELL MANUFACTURING COMPANY, OF EAST HAMPTON, CONNECTICUT, A CORPORATION OF CONNECTICUT.

BASE FOR TOY TELEPHONES.

Application filed June 8, 1922. Serial No. 566,902.

To all whom it may concern:

Be it known that I, CLIFFORD M. WATROUS, a citizen of the United States, and a resident of East Hampton, in the county of Middlesex and State of Connecticut, have invented certain new and useful Improvements in Bases for Toy Telephones, of which the following is a full, clear, and exact description, whereby anyone skilled in the art may make and use the same.

The invention relates to toy telephones and is particularly directed to the base portion of such a toy.

A toy telephone of the character illustrated in the drawings is shown and described in my Patent No. 1,419,902, dated June 13, 1922, and the base hereinafter described is applicable to such a toy.

The object of the invention is to provide a resilient base which may be cheaply and economically manufactured and applied to a toy. It presents a finished appearance to the base and covers all sharp edges which are liable to mar or scratch polished surfaces of tables and the like, when used by children.

Referring to the drawings:

Figure 1, is a view in elevation of the toy telephone illustrating one form of resilient base.

Figure 2, is a sectional view through the base.

Figure 3, illustrates the resilient element inserted within the base.

Figure 4, is a fragmentary detail, showing a modified form of resilient buffer.

Figure 5, is a fragmentary view illustrating a special modification of resilient base insert.

As described in my patent referred to, I have shown a toy telephone of finished design which simulates the standard telephone set which is in almost universal use.

Such a toy must, of necessity, be manufactured at a low cost and therefore the parts are made up from stampings or spun metal.

While the surfaces may be highly finished to make an attractive toy, the edges of the stamped up parts are more or less uneven and rough and require special finishing.

It is one of the objects of the present invention to overcome the expense and difficulties of high finishing on the edges of the

base part and provide a buffer or protector of a resilient character which will prevent the base from scratching or scarring highly polished surfaces.

Children, of course, when using a toy of this character move it about upon the tables and other articles of furniture, and if there are any sharp edges upon the base they will, of course, mar and deface the polished surfaces.

In order to overcome these objections, and at the same time, give a highly finished appearance to the toy, I provide a resilient base structure which may readily be sprung over the base portion of the telephone or sprung within the base. In either case, the appearance of the toy is improved and a safeguard is provided so that a child may use it with impunity and without liability of marring or scarring tables or other articles of furniture. Furthermore, it protects the child from possible abrasions of the hands or face which might result from sharp edges upon the drawn or spun up metallic base.

In the accompanying drawings, in Figure 1, there is illustrated a toy telephone such as described in my co-pending application. It is not necessary herein to describe the particular gong striking mechanism and other elements, as the base is applicable to various forms of toy devices of the character indicated.

Numeral 1, denotes a base which is preferably stamped or spun up from sheet metal and has surmounting it, a standard 2, which in turn supports a transmitter element 3, and mouthpiece 4. The standard 2, also has clamped to it a gong 5, and its mechanism.

The mechanism is actuated by a receiver hook lever 6, within which may be held a toy receiver 7. A replica of the usual connections, from the base 1, to the receiver 7, is secured by a cord 8.

These parts make up the general elements of receiving and transmitting telephone sets.

The resilient base, as illustrated in Figures 1, and 2, consists of a fabric or other resilient material 9, which covers a plate 10. The plate 10, has an upwardly extended flange 11, said plate being preferably formed from drawn up sheet metal.

The fabric or other resilient material

covers the entire outer surface of the plate 10, and is carried over the flange 11, extending under the base part of the telephone.

Concentrically arranged in the plate 10, 5 is a drawn up nipple 13. This serves as a countersink for the head 14, of a screw 15, by which the plate and appurtenant parts together with the base 1, are secured to the standard 2.

- 10 The nipple 13 is pierced as at 15', for the passage of the screw and the upturned nipple serves a further purpose in that it provides a slight chamber 16, between the plate 10, and a base plate or disc 17.
- 15 The plate or disc 17, rests upon the lower edge 18, of the base 1. The chamber 16, affords a convenient space for the lapped over portion of the resilient material 19, which extends under the plate or disc 17.
- 20 In practice, the resilient material is passed over the plate 10 and its flange 11, and is held loosely in place by cross stitching 20, or other suitable means of holding the fabric or resilient material in place for 25 purposes of assembly.

In assembling the parts, the plate 17, is laid upon the base 1, and the plate 10, with its fabric or other resilient covering, is forced up over the lower end 21, of the base 30 1, the screw 15, is then passed thru the perforation 15', of the nipple 13, and a perforation 22, in the plate 17, registering therewith. This firmly secures the parts together and forms a solid base so that the fabric or resilient material cannot be punctured or 35 removed.

It will be noted that the head 14, of the screw 15 passes up into the nipple 13, and is above the plane and surface of the plate 40 10, and its cover.

In Figure 3, the resilient base elements are illustrated as being held within the base part 1. In this form of device, the plate 23 has an upturned flange 24, said plate and 45 flange being enveloped in the fabric or resilient material 25.

The plate 23, has an upwardly extending nipple 26, which, in conjunction with the plate or disc 27, forms the chamber 28, for 50 the reception of the overlying portion of the fabric or resilient material.

These plates with the clamped in fabric or resilient material are forced within the base 1, and secured by the screw 28', which 55 holds the resilient base parts, the base 1, and standard together.

In Figure 4, there is a similar arrangement to that of Figure 3, but in this case there is a spoked frame 29, having a peripheral rim 30, which rim is covered by 60 the resilient material 31.

This latter construction affords a very

light framework for securing the fabric or resilient material in place and it is an economical construction inasmuch as it requires 65 less fabric or resilient material to cover the rim 30, as compared with covering the whole of the base plate as in Figures 2 and 3. In fact, the rim 30, may be wound with a suitable resilient material of stripped form, 70 thus affording a suitable buffer for the base of the telephone.

In lieu of the forms above described and to prevent the showing of any fastening devices through the base, a split spring ring 75 32, may be covered with a fabric or resilient pad 33, and expanded within an annular groove 34, in the base. Where such a construction is employed, it is advisable to use a plate 35, to prevent puncturing of the resilient buffering material.

The advantages of the base, in any of its forms, will be at once apparent. It not only embellishes the toy but safeguards the more or less sharp edges of the base thus giving 85 a protection to both the child using the toy and to articles of furniture upon which the toy may be moved about.

What I claim as my invention and desire to secure by Letters Patent is:

1. In combination with a toy telephone, a base, a flanged disc extending about the base, a superimposed clamping member and resilient material covering the disc and flange and extending below the superimposed member and means for clamping said disc and superimposed member, and intermediate covering material of the disc.

2. In combination with a toy telephone, a base, a flanged disc, a resilient covering for said disc and its flange, a plate fitting within the flanged disc and means for securing the flanged disc, plate and telephone base together and forming a clamp for the resilient covering material.

3. A base for telephones consisting of a flanged plate or disc, a plate fitting within said flanged plate and a resilient material covering the flanged plate and extending between the same and the interior plate and means for securing said parts to the base.

4. A base for telephones consisting of a flanged plate, a concentrically formed nipple in said plate having a perforation, a centrally perforated disc or plate fitting within the flanged plate, a resilient covering for the flanged plate extending between the same and the interior disc, and means for clamping said plates together and to the telephone base.

CLIFFORD M. WATROUS.
